UNITED STATES PATENT OFFICE

2,107,853

FLOOR RACK

George E. Coffey, Chicago, Ill., assignor to Harold S. Russell, Chicago, Ill.

Application July 10, 1936, Serial No. 90,018

9 Claims. (Cl. 20—78)

The floor rack of the present invention is intended primarily for use of the floors of refrigerator cars or the like and to be substituted in place of the wooden floor racks now commonly in use.

The floor rack of the present invention together with the supports therefor are of metallic construction, which possesses positive advantages in comparison with wooden floor racks, in that the danger of distortion due to swelling or shrinking is eliminated, so that a more even and uniform surface is presented for the storage and movement of the commodities housed within the car or other structure. The present invention, moreover, makes provision for increased circulation of air and eliminates the possibility of impairment due to splintering or other injury to the floor surface by reason of inequalities which might serve as abutments or obstructions in the shifting of the load and which, in the case of wooden floors, constitutes a serious objection.

A further advantage lies in the fact that the metallic slats are of uniform thickness, so that, in the case of repair or replacement, exact dimensions will be maintained, which accurate fitting is often omitted in the repairing of wooden slatted floors where new slats of non-uniform thickness are employed as replacements, resulting in inequalities in the floor surface.

Further objects and details of the present invention will appear from a description thereof in conjunction with the accompanying drawings, wherein,—

Fig. 1 is a plan view showing the slatted surface of a refrigerator car floor, the view showing one half of the length of the car;

Fig. 2 is a sectional elevation of the same, showing the manner of folding the slatted sections into vertical relation to the car walls;

Fig. 3 is an enlarged detail showing the preferred construction of the slatted panels;

Fig. 4 is a sectional elevation taken on line 4—4 of Fig. 3;

Fig. 5 is a sectional detail taken on line 5 of Fig. 3;

Fig. 6 is a plan view of a modified form of construction;

Fig. 7 is an edge view of the same; and

Fig. 8 is a sectional detail taken on line 8—8 of Fig. 6.

Referring particularly to the construction first illustrated, the slatted flooring of the car consists of a plurality of sections A each of which consists of slatted panels 10, 11, 12. Each panel is integrally formed of plate metal which is pressed

or fabricated to afford upstanding ribs 13 in the nature of slats which are separated from one another by valleys 14. The ribs comprise flat top walls 15, all of which lie in the same plane to present a flush surface for the support of the kegs, boxes, crates, packages or the like, which constitute the lading of the car. The ribs also comprise upstanding side walls 16 which are connected by base walls 17 constituting the floors of the valleys between the ribs. The terminal rib 10 of a panel has the lower edge of its outer side wall turned in to afford a flange 18, leaving an open space or gap between the panel and the next contiguous panel in the same section of the floor. The top walls 15 are provided with lines of apertures 19 each of which has a downturned marginal flange 20, which serves to reinforce and stiffen the construction. The gaps between the panels are of equal width with the valleys, so that the spacing of the slat-like ribs is uniform from end to end of the car floor.

The innermost section A, as shown, has hinged thereto a center section B connected by hinges 21 with the contiguous section A. The hinged section B occupies a space immediately adjacent to the transverse center line of the car and adjacent to the car door, and the hinges 21 are provided to enable this section to be folded inwardly upon the adjacent section A, which may be swung up into the position shown in dotted lines in Fig. 2 against the side wall of the car, the sections being mounted upon hinges 22.

In order to increase the circulation of air, the floors of the valleys between the ribs are provided with elongated apertures 23, which gives to the slatted construction as a whole the character of a foraminous surface to facilitate the flow of air without sacrifice of the stiffness and rigidity required in a structure of this character.

The slatted sections, each comprising three panels in the form shown, are supported upon stringers 24 which, as shown, extend lengthwise of the car and which are of channel construction standing on edge to afford a vertical wall 25, and top and bottom walls 26 and 27, which latter are reinforced at recurrent intervals by vertical plates 28 provided with flanges 29, which plates constitute spacers and which are preferably spot welded in position to further strengthen the stringers to the necessary extent. As shown, the stringers 24 are imperforate, since they extend lengthwise of the car and do not obstruct the flow of air beneath the lading, although, if desired, the walls of the stringers 24 may be provided with apertures.

The hinges 22 comprise hinge members 30 in the form of brackets secured to the floor sections in conjunction with fixed brackets 31 of angular formation fitted into the angle between the 5 floor and the wall of the car, which members are pivoted together upon a pintle 32. It is preferred to spot weld the panels directly to the stringers, although other means of securement may be employed.

10 Although in the construction described, the slatted surfaces run crosswise of the car, and the stringers run lengthwise thereof, a reversal of this arrangement is contemplated if desired, and it is not the intention to limit the invention to 15 the arrangement shown by way of exemplification in the drawings.

The construction shown in Fig. 6 illustrates a 20 slat arrangement in which the metallic slats 33 run lengthwise of the car and are supported upon 25 stringers 34 running crosswise of the car. In this construction, instead of providing a multiplicity of slats in the form of ribs struck upwardly from an integral plate of metal, the slats are individually formed, each slat comprising a top wall 35 and side walls or flanges 36, which are inturned at their lower edges to afford flanges 37 which rest upon the underlying stringers. In this case the individual slats are provided in their top walls with flanged apertures 38 like 30 those first described.

In order to hold the stringers 34 in elevated 35 relation to the car floor, each of the stringers is provided with feet 39 which, as shown, are of trough-shaped formation comprising a base 40 and diverging side walls 41 which are spot welded or otherwise connected at their upper edges to the stringer.

The stringers 34 are of inverted channel formation comprising a top wall 42 and flanged 40 side walls 43, and since the stringers are held in elevated relation by the feet 39, it will not ordinarily be necessary to provide apertures in the stringers for the circulation of air, although such apertures may be provided if desired. As shown 45 in Fig. 6, the slatted section C comprises a plurality of individual slats mounted upon transversely extending stringers, and the center section D is secured to the end of the section C by hinges 44 to enable the section D to 50 be swung inwardly against the section C when the latter is turned upwardly upon its hinges 45.

Although in the form of construction shown 55 in Fig. 6 the slats extend lengthwise of the car, and the stringers extend transversely, it is obvious that a section of this construction might be otherwise arranged to bring the slats into transverse relation to the car body.

In either form of construction, full provision 60 is made for the circulation of the air which flows longitudinally of the car along the car floor and up through the interstices afforded between the slats, whether the latter be formed integrally or 65 individually. The slats and stringers, being of channel formation, afford great rigidity, and at the same time the method of connecting the parts by spot welding or the like prevents the 70 possibility of displacement or distortion due to warping or rotting of the material. This also prevents the springing up of individual slats due to warping, with a resultant impairment in the plane relation of the floor surface, which, when it occurs, interposes an impediment in the shifting of cargo, which often results in a tearing loose of a slat or a splintering of the same where 75 wooden slats are employed.

Furthermore, the employment of metal eliminates the absorption of moisture with resultant odors, which in the case of wooden slatted cars are frequently present and difficult to eliminate, and are most objectionable in the transportation 5 of foodstuffs or the like which may be contaminated by such odors.

The construction employing integral panels possesses certain special advantages in reduction 10 of manufacturing costs and in rigidity of construction, since the spacing of the slats is inherent in the panel itself and is not dependent upon the connection of the slats to the stringers as in the case of the individually formed slats.

Furthermore, by maintaining accurate spacing 15 of the slats, the gaps between the same may be reduced to the extent necessary to prevent the lodgment of materials between the slats, and by the maintenance of uniformity in the plane of the slatted floor surface, the movement and 20 storing of commodities is facilitated.

Although the invention has been described with particularity as to detail, it is not the intention to limit the invention to the forms of construction shown, since modifications thereof 25 are within the scope of the invention.

I claim:

1. A slatted floor for cars or the like, comprising integrally formed metallic panels, each panel having formed therein a plurality of upstanding 30 riblike members having flat top walls lying in a uniform horizontal plane and constituting slats with intervening valleys, and stringers located beneath the panels and extending transversely with respect to the slats formed therein for elevating the panels above the floor level of the car or the like.

2. A slatted floor for cars or the like, comprising integrally formed metallic panels, each panel having formed therein a plurality of upstanding 40 riblike members having flat top walls lying in a uniform horizontal plane and constituting slats with intervening valleys, the slats being provided with downwardly flanged apertures to promote the circulating of air therethrough, and stringers located beneath the panels and extending transversely with respect to the slats formed therein 45 for elevating the panels above the floor level of the car or the like.

3. A slatted floor for cars or the like, comprising integrally formed metallic panels, each panel having formed therein a plurality of upstanding 50 riblike members having flat top walls lying in a uniform horizontal plane and constituting slats with intervening valleys, the slats being provided with downwardly flanged apertures to promote the circulating of air therethrough and the valleys being provided with apertures for a like purpose, and stringers located beneath the panels and extending transversely with respect to the slats 55 therein formed for elevating the panel above the floor level of the car or the like.

4. A slatted floor for cars or the like, consisting of separate sections, each section composed of a plurality of panels, each panel being formed of a 60 metal and configured to afford a plurality of parallel upstanding ridges having flat top walls lying in a uniform horizontal plane and constituting slats with intervening valleys, and a plurality of stringers extending beneath the panels composing 65 a section and adapted to hold the panels in elevated relation above the level of the car floor.

5. A slatted floor for cars or the like, consisting of separate sections, each section composed of a plurality of panels, each panel being formed of 70

- 5 metal and configured to afford a plurality of parallel upstanding ridges having fiat top walls lying in a uniform horizontal plane and constituting slats with intervening valleys, the slat surfaces being apertured to facilitate the distribution of air, and a plurality of stringers extending beneath the panels composing a section and adapted to hold the panels in elevated relation above the level of the car floor.
- 10 6. A slatted floor for cars or the like, consisting of separate sections, each section composed of a plurality of panels, each panel being formed of metal and configured to afford a plurality of parallel upstanding ridges having fiat top walls lying in a uniform horizontal plane and constituting slats with intervening valleys, the slat surfaces being apertured to facilitate the distribution of air and the valleys being apertured for a like purpose, and a plurality of stringers extending beneath the panels composing a section and adapted to hold the panels in elevated relation above the level of the car floor.
- 15 7. A slatted floor for refrigerator cars, consisting of spaced parallel metallic slat members of inverted channel formation each comprising a horizontal top wall and depending vertical side walls, the top walls all lying within the same horizontal plane and being provided with apertures to promote the circulation of air, and a mounting for the slat members positioned to hold the slat members in elevated relation to the floor level of the car.
- 20 8. A slatted floor for refrigerator cars, consisting of spaced parallel metallic slat members of inverted channel formation each comprising a horizontal top wall and depending vertical side walls, the top walls all lying within the same horizontal plane and being provided with downwardly flanged apertures to promote the circulation of air, and a mounting for the slat members positioned to hold the slat members in elevated relation to the floor level of the car.
- 25

the top walls all lying within the same horizontal plane, and a mounting for the slat members positioned to hold the slat members in elevated relation to the floor level of the car.

8. A slatted floor for refrigerator cars, consisting of spaced parallel metallic slat members of inverted channel formation each comprising a horizontal top wall and depending vertical side walls, the top walls all lying within the same horizontal plane and being provided with apertures to promote the circulation of air, and a mounting for the slat members positioned to hold the slat members in elevated relation to the floor level of the car.

9. A slatted floor for refrigerator cars, consisting of spaced parallel metallic slat members of inverted channel formation each comprising a horizontal top wall and depending vertical side walls, the top walls all lying within the same horizontal plane and being provided with downwardly flanged apertures to promote the circulation of air, and a mounting for the slat members positioned to hold the slat members in elevated relation to the floor level of the car.
